G. T. EPLING

HAND GUARD AND DECIDUOUS TOOTH ERUPTER

Filed Oct. 20, 1923

Inventor
G. T. Epling

Watson E. Coleman
Atty

UNITED STATES PATENT OFFICE.

GILES T. EPLING, OF WELCH, WEST VIRGINIA.

HAND GUARD AND DECIDUOUS-TOOTH ERUPTER.

Application filed October 20, 1923. Serial No. 669,787.

To all whom it may concern:

Be it known that I, GILES T. EPLING, a citizen of the United States, residing at Welch, in the county of McDowell and State of West Virginia, have invented certain new and useful Improvements in Hand Guards and Deciduous-Tooth Erupters, of which the following is a specification, reference being had to the accompanying drawings.

This invention relates to hand guards and deciduous tooth erupters and has relation more particularly to a device of this general character especially designed and adapted for use by infants and it is an object of the invention to provide a device of this general character embodying novel and improved means whereby the infant is prevented from sucking upon the digits of the hand and also to permit its use by the infant when teething.

The invention consists in the details of construction and in the combination and arrangement of the several parts of my improved hand guard and deciduous tooth erupter whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a view in perspective of a hand guard and deciduous tooth erupter constructed in accordance with an embodiment of my invention and in applied position; and

Figure 2 is a longitudinal sectional view taken through the device as illustrated in Figure 1, an inserted hand being diagrammatically indicated by broken lines.

As disclosed in the accompanying drawings, G denotes a guard and erupter constructed in accordance with an embodiment of my invention and which is formed of rubber or like material and which device is of a substantially fixed formation with the walls, however, possessing sufficient elasticity to permit the same to yield so that undue hindrance or interference with the movements of the hand and fore-arm is

avoided and also to prevent injury to such parts of the anatomy.

My improved guard and erupter G comprises an outer closed end portion 1 parti-spherical or globular and provided with an opening 2 through which a hand of the infant is adapted to pass when inserted within said outer or closed end portion. The opening 2 is defined by a substantially cylindrical sleeve 3 of desired length and which is adapted to substantially snugly engage around the fore-arm inwardly of but in close proximity to the wrist so that the infant may have relative free movement of the hand when applied within the guard. The free end portion of the sleeve 3 at substantially diametrically opposed points is provided with the slots 4, said slots being spaced lengthwise of the device but disposed in a circumferential direction.

Selectively engaged through the desired slots 4 is a tape 5 with its end portions in overlying relation. A safety pin 6 or the like is disposed through the free end portions of the tapes and provides means whereby the tapes may be engaged with the sleeve of a body garment so that the guard is effectually held against displacement when applied. The spacing of the slots 4 permits adjustable connection of the tapes with the device as the occasions of practice may require.

The wall of the parti-spherical or globular portion 1 of the device is provided with the openings 7 to lighten the weight of the device G and also to permit the circulation of air therethrough when in applied position.

The outer or closed end of the portion 1 is provided thereacross with the substantially radially disposed and outstanding lip or flange 8 of rubber or kindred material and of such thickness to permit said lip or flange to be readily engaged between the gums of an infant to facilitate the cutting of the teeth. Furthermore this lip or flange 8 serves to provide a means whereby a child, that has been sucking its thumb or finger, will not be frightened of the device. In a case where the child is nervous to the extent that the device cannot be used, the device can be given the child to play with until it gets used to it and after which time it can be applied over the hand for the purpose of breaking the infant from the habit of placing its digits in the mouth.

1 The parti-spherical or globular portion 1 of the device is of such diameter to prevent its insertion within the mouth of a child a length sufficient to do any damage. After 5 the child has passed the teething age, the lip or flange 8 may be readily removed with a pair of scissors or other severing instrument.

10 The lip or flange 8 is also provided at points therealong with the openings 9 in order to lighten the weight of the device.

15 It has been fully demonstrated in practice that my improved hand guard and deciduous tooth erupter will in the majority of cases prevent the habit of thumb sucking being acquired. The lip or flange 8 which the child will insert in its mouth will not enter into the tongue side of the mouth far enough to exert pressure that would change the continuity 20 or formation of the growing jaw bones. The openings 9 in the lip or flange 8 together with the openings 7 in the adjacent part of the portion 1 which comes in contact with the lips will allow air to be drawn there- 25 through so that no part of the guard will come into the vestibule or between the jaw bones. With the use of my device it is impossible for the child to get the lip or flange 30 8 at an angle that would distort or disfigure the maxilla (upper jaw bone) or the mandible (lower jaw bone).

35 My improved device provides a safe and sure means of preventing many children from having irregular teeth, displacements of the jaws at the condyle meniscus which would render the jaws and teeth incapacitated for masticating the food properly, causing decay of the teeth and diseases of the gums as well as all of the diseases which 40 are resultant from children not receiving proper nutrition.

From the foregoing description it is

thought to be obvious that a hand guard and deciduous tooth erupter constructed in accordance with my invention is particularly 45 well adapted for use by reason of the convenience and facility with which it may be assembled and operated, and it will also be obvious that my invention is susceptible of some change and modification without departing from the principles and spirit there- 50 of and for this reason I do not wish to be understood as limiting myself to the precise arrangement and formation of the several parts herein shown in carrying out my in- 55 vention in practice except as hereinafter claimed.

I claim:—

1. As a new article of manufacture, a hand guard and deciduous tooth erupter 60 comprising a globular body adapted to house the hand and provided in its wall with an opening through which the hand is inser- 65 tible, and an erupter flange extending outwardly from the outer end of the globu- 70 lar body.

2. As a new article of manufacture, a hand guard and deciduous tooth erupter comprising a globular body adapted to house the hand and provided in its wall with an 75 opening through which the hand is inser- 80 tible, and an erupter flange extending outwardly from the outer end of the globular body, said flange being disposed radially of the body.

3. As a new article of manufacture, a hand guard and deciduous tooth erupter comprising a member adapted to house a hand, and an erupter flange extending outwardly from the outer end of the member and upon which 85 the child is intended to bite.

In testimony whereof I hereunto affix my signature.

GILES T. EPLING.
